TELEPHONE PAY STATION APPARATUS

William J. Vincent, Rochester, N. Y., assignor to
 Rochester Telephone Corporation, Rochester,
 N. Y., a corporation of New York

Application October 23, 1934, Serial No. 749,571

10 Claims. (Cl. 194—16)

This invention relates to coin collecting devices and more particularly to means for preventing the fraudulent removal of coins from telephone coin collecting devices.

5 In coin collecting devices of the prepayment type such as are commonly used at telephone pay stations, it is the practice to refund the deposited coin or coins to patrons when calls are not completed. This practice has afforded an 10 opportunity for dishonest patrons to operate these devices so that the coins, deposited therein in the course of making calls, are returned to such patrons even when the calls are completed, thereby defrauding the telephone company of 15 money which should be collected.

As is well known, such a coin collecting device includes a coin trap which holds the deposited coin or coins until the time of collection and it also includes a coin vane directly operated by 20 current of two different polarities selectively applied from a telephone exchange, either to collect the deposited coin or coins for the telephone company when the call is successful or to return them to the patron if the call is not completed. 25 In the past, unscrupulous individuals have been able to insert thin strips of material into the device from the exterior of its housing to move the coin vane in a direction to refund all deposited coins. In certain other instances dishonest persons have gained access to the interior of the device and have either manually operated the coin vane to refund the coin or coins or have disconnected the extension pin on the coin vane from the magnetically-operated arm 30 which normally actuates it to collect or to refund the coin, so that the vane could be tilted to refund all coins deposited in the device.

In accordance with the present invention, means are provided so that the coin vane cannot 35 be tilted to the refund position manually from the interior of the housing of the device or by means of a thin strip inserted into the device through a joint in its housing.

A further feature of the invention relates to an 40 electromagnetically actuated latch operable only by the application of coin refunding current from the telephone exchange, which latch locks the coin vane so that it cannot be fraudulently tilted to the coin refunding position. 45

50 In accordance with still another feature of the invention, means are provided which render it exceedingly difficult for an unauthorized person to disconnect the extension pin on the coin vane from the magnetically operated arm of the coin 55 collecting device.

These and other features of the invention will appear from the detailed description and claims when taken with the drawing in which Fig. 1 is a front elevation of the electro-magnetically operated unit of a coin collecting device of the character above referred to; Fig. 2 is a side elevation and Fig. 3 is a plan view of the unit of Fig. 1; Fig. 4 is a detailed view of the latch mechanism for preventing fraudulent operation of the coin vane; and Fig. 5 is a cross sectional view taken on the line 5—5 of Fig. 1 illustrating the means for preventing the unauthorized disconnection of the extension pin on the coin vane from its operating arm.

The invention herein disclosed is intended for 15 incorporation in a coin collecting device of the character disclosed in the patent to Forsberg, #1,043,219, granted November 5, 1912. The housing of the device shown in that patent as well as the coin chutes, the coin trigger, the coin trap 20 and the coin vane may remain unchanged. However, the electro-magnetic unit of that device, while structurally the same as that shown in the patent disclosure, has incorporated therein the structure of the present invention. 25

This electro-magnetic unit includes a yoke 5 on which there is mounted in spaced relation, the cores 6 and 7 which have their upper ends cut away to form pole-pieces 8 and 9. Solenoid windings 10 and 11 respectively encircle cores 6 and 7. 30 A permanent magnet 12 has its lower end attached to yoke 5 by means of screw 13, while the upper end 7 of this magnet extends substantially into the plane of the upper ends of the pole-pieces 8 and 9. A U-shaped frame 14 apertured 35 to receive pole-pieces 8 and 9, is attached by screws to the ends of cores 6 and 7. This frame is provided with uprights 15 and 16 and with cut-out portion 17 through which the upper end of the permanent magnet 12, projects. A bracket 40 18 has its intermediate portion pivoted at 19 and 20 in the uprights 15 and 16 and has fixedly secured to its under-side, a permanent magnet 22 so that the free ends of this magnet can rock 45 toward the pole-pieces 8 and 9. It will be noted that the armature by reason of its mounting on the bracket 18 has its intermediate portion adjacent the free end of the upwardly extending permanent magnet 12. Stops in the form of extensions 23 and 24 on the bracket 18 are arranged to engage portions of the frame 14 to limit the rocking movement in either direction of this bracket as well as the armature 22 attached to it. Stop arms 25 and 26 individually pivoted 50 at 19 and 20, and provided with extensions 27 and 55

28, are urged downwardly by springs (not shown) to engage the ends of the pole pieces 12 and 13, so that these arms tend to limit the upward swinging movement of each end of the armature 22, all in accordance with well-known practice. The bracket 18 has an integral arm 30 projecting at right angles thereto through the cut-out portion 17 of the frame, which arm terminates at its lower end in a forked offset portion 31. This forked portion is adapted to receive the extension pin 32 forming a part of the well-known coin vane 33, which is tiltable in one direction to collect the coin or in the opposite direction to refund the coin to the patron. The device includes 10 a coin trigger 34, a coin trigger lever 35, a coin trigger lever spring 36, inner ground contact spring 37 and the outer ground contact spring 38 which are identical in construction and function with the corresponding parts disclosed in the 15 mentioned Forsberg patent and need not be further described herein.

In the past dishonest persons have been able to insert a thin strip of substantially rigid material through a joint between pieces of the housing of the device to swing the arm 30 as shown 20 in Fig. 1 toward the left, thereby tilting the coin vane 33 to a position to refund the deposited coin or coins. In accordance with the present invention, means are provided which substantially eliminate all possibilities of such fraudulent operation of the device. In a preferred form of this means, the pole-piece 9 is provided with an opening therethrough, extending generally in the direction of the long axis of the armature 22. 25 A latch 40 in the form of a plug or cylinder of magnetic material is mounted in this opening. This plug has an enlarged head at one end so that it cannot move to the left beyond the position shown in Fig. 1, and has secured thereto at 30 its other end, an extension 41 of the same diameter as the plug but formed of non-magnetic material such as brass. This extension normally projects into the path of the right hand end of the armature 22 as shown in Fig. 1, so that the 35 mentioned end of the armature cannot be tilted downward when the latch is in its normal position and therefore the arm 30 attached to this armature and its offset portion 31 are prevented from being moved to tilt the coin vane 33 to its 40 refund position. An arcuate pole-piece 42 of electromagnetic material is fixedly mounted on the frame 14 in slightly spaced relation from the pole-piece 9 and from the head of the plug 40. A leaf spring 43 of non-magnetic material such as brass 45 has its ends engaging the ends of the piece 42 while its intermediate portion is bowed to engage the head of the plug in order to hold it in normal position as shown in Figs. 1 and 4. A cover 44 of non-magnetic material such as brass mounted by means of screws 45 on the pole-piece 42 enclose the major portion of the latch mechanism and therefore renders the latch extension 41 inaccessible from the front of the unit so that 50 an unauthorized person cannot mechanically operate the latch 40, while this latch, in its normal position prevents the manual tilting of the coin vane of the device.

It will be understood that the pole-piece 42 is in the path of the flux leakage from the solenoid 11 to the pole-piece 13 so that when the toll operator at the central exchange transmits the coin refunding current, this current will be of such polarity that the solenoid winding 11 will be energized and at the same time the flux leaking from the winding 11 through the pole-piece

42 to the pole-piece 13 will attract the plug or latch 40 toward the right as shown, so that its extension 41 will be withdrawn from the path of the right hand end of the armature 22. The energization of the winding 11 also causes the 5 right hand end of the armature 22 to rock downwardly and since the extension 41 of the latch is now out of its path, this portion of the armature will swing downwardly toward the frame 14 until its movement is stopped by stop 24. This 10 movement of the armature swings the lower forked end 31 of the arm 30 in a clockwise direction and this arm through its engagement with the extension pin 32 on the coin vane tilts this 15 vane to the coin refund position. Thus the coin vane can be tilted to the refund position only when the latch 40 is electrically operated or drawn into the pole-piece 9 by current transmitted under operator control from the telephone exchange. 20

It has also been discovered that unauthorized persons frequently gain access to the interior of the housing of the coin collect mechanism and depress the arm 30 toward the permanent magnet 12 as best shown in Fig. 2 so that the forked 25 portion 31 of this arm is disengaged from the pin extension 32 on the coin vane 33. When the pin extension 32 is thus disengaged, the vane can be tilted so that all coins will be refunded. In accordance with a further feature of the present 30 invention, an adjustable collar 46 is clamped to the permanent magnet 12 by means of a bolt 47 in such a position that the collar presents its surface 48 close to the right hand surface of the arm 30 as illustrated in Fig. 2 and thereby prevents this arm from being bent toward the right with the result that the forked portion 31 of the arm cannot be disconnected from the coin vane pin extension. The bolt 47 is placed in a rather 35 inaccessible position and since a person attempting to fraudulently operate the device, must act very quickly, the collar 46 presents such a handicap as to prevent the disconnection of coin vane pin extension 32 from the arm 30 so that the coin vane cannot be permanently tilted to the refund 40 position. 45

What I claim is:

1. In a coin collecting device, a polarized electro-magnetic unit having an armature movable in one direction in response to operating current 50 of one polarity and movable in the other direction in response to current of the opposite polarity, and means normally locking said armature against movement in one direction, said means being unlocked and said armature being moved 55 by the energization of said electromagnet in response to current of one polarity.

2. In a coin collecting device, a polarized electromagnetic unit having an armature movable in one direction in response to operating current 60 of one polarity and movable in the other direction in response to current of the opposite polarity, and a latch normally preventing movement of said armature in one direction, said latch being withdrawn by leakage flux from said electromagnetic unit when said unit is energized 65 in response to current of one polarity.

3. In a coin collecting device, a polarized electromagnetic unit provided with a pair of pole-pieces, an armature pivotally mounted intermediate its ends and having its ends respectively positioned adjacent each pole-piece, one of said pole-pieces having an opening therein, a latch of magnetic material in said opening, said latch having a portion normally extending into the 70 75

- path of movement of one end of said armature, and a secondary pole-piece of magnetic material supported adjacent said last-mentioned pole-piece and said latch in the path of leakage flux from a portion of said electromagnetic unit whereby the energization of said unit in one sense withdraws the latch from the path of movement of said armature and attracts the adjacent end of said armature.
4. In a coin collecting device, a polarized electromagnetic unit provided with a pair of pole-pieces, an armature pivotally mounted intermediate its ends and having its ends respectively positioned adjacent each pole-piece, one of said pole-pieces having an opening therein, a latch having an extension of non-magnetic material normally projecting into the path of movement of one end of said armature, and a secondary pole-piece of magnetic material supported adjacent said last-mentioned pole-piece and said latch in the path of leakage flux from a portion of said electromagnetic unit whereby the energization of said unit in one sense withdraws the latch from the path of movement of said armature and attracts the adjacent end of said armature.
5. In a coin collecting device, a polarized electromagnetic unit provided with a pair of pole-pieces, an armature pivotally mounted intermediate its ends and having its ends respectively positioned adjacent each pole-piece, one of said pole-pieces having an opening therein, a latch having an extension of non-magnetic material normally projecting into the path of movement of one end of said armature, a secondary pole-piece of magnetic material supported adjacent said last-mentioned pole-piece and an end of said latch in the path of leakage flux from a portion of said electromagnetic unit whereby the energization of said unit in one sense withdraws the latch from the path of movement of said armature and attracts the adjacent end of said armature, and a shield substantially enclosing said latch.
6. In a coin collecting device, a polarized electromagnetic unit provided with a pair of pole-pieces, an armature pivotally mounted intermediate its ends and having its ends respectively positioned adjacent each pole-piece, one of said pole-pieces having an opening therein, the axis of said opening extending in the direction of the main axis of said armature, a latch of magnetic material in said opening, said latch having an extension of non-magnetic material normally projecting into the path of movement of one end of said armature, and a secondary pole-piece of magnetic material supported adjacent said last-mentioned pole-piece and facing the opening therein in the path of leakage flux from a portion of said electromagnetic unit whereby the energization of said magnet in one sense withdraws the latch from the path of movement of said armature and attracts the adjacent end of said armature.
7. In a coin collecting device, a coin vane, a polarized electromagnetic unit having an armature movable in one direction in response to operating current of one polarity and movable in the other direction in response to current of the opposite polarity, an arm of flexible material mounted for swinging movement under the control of said armature, said arm having a portion engaging said coin vane, and means normally preventing said arm from being bent out of engagement with said coin vane.
8. In a coin collecting device, a coin vane, a polarized electromagnetic unit having solenoids each provided with a core mounted in spaced relation, an armature pivotally mounted at an intermediate point thereof adjacent said solenoids, whereby the ends of said armature respectively swing toward said cores, a member mounted between said cores and extending generally parallel to the main axes thereof, an arm of flexible material carried by said armature, said arm having a portion normally engaging said coin vane, and a stop carried by said member normally preventing the disengagement of said arm from said coin vane.
9. In a coin collecting device, a coin vane, a polarized electromagnetic unit having solenoids, each provided with a core mounted in spaced relation, an armature pivotally mounted at an intermediate point thereof adjacent said cores whereby the ends of said armature respectively swing toward said cores, a permanent magnet mounted between said cores and extending generally parallel to the main axis thereof to a point adjacent the intermediate portion of said armature, a flexible arm carried by said armature, said arm having a portion normally engaging said coin vane, and a stop carried by said permanent magnet normally preventing the disengagement of said arm from said coin vane.
10. In a coin collecting device, a polarized electromagnetic unit provided with spaced solenoids, each having a core terminating in a pole-piece, an armature pivotally mounted intermediate its ends, having its ends respectively positioned adjacent each pole-piece, one of said pole-pieces having an opening therein, the axis of said opening extending in the direction of the principal axis of said armature, a latch of magnetic material in said opening, said latch having an extension of non-magnetic material normally projecting into the path of movement of one end of said armature, said latch also being provided with a stop engaging a portion of its related pole-piece to limit the movement of said latch in one direction, a secondary pole-piece of magnetic material supported on the solenoid of and adjacent said last-mentioned pole-piece in the path of the leakage flux from said solenoid whereby the energization of said solenoid in one sense withdraws the extension on said latch from the path of movement of said armature and attracts the adjacent end of said armature, a leaf spring of non-magnetic material having its ends respectively engaging said secondary pole-piece and its intermediate portion engaging said latch to force it into its normal position determined by said stop, and a shield of non-magnetic material substantially enclosing said latch.

WILLIAM J. VINCENT.
